Patented Feb. 20, 1962

192,280

GARMENT HANGER

Jack M. Zuckerman, Elmhurst, N.Y., assignor to Yankee Plastics, Inc., New York, N.Y., a corporation of New York

Filed June 28, 1961, Ser. No. 65,752

Term of patent 14 years

(Cl. D80—8)

FIG. 2

FIG. 1 is a front elevational view of a garment hanger, showing my new design, the rear being essentially the same; and

FIG. 2 is a top plan view thereof.

I claim:

The ornamental design for a garment hanger, substantially as shown and described.
